UNITED STATES PATENT OFFICE

2,108,488

TUBULAR BELT CONVEYER

Henry Stinson Johns, North Grimsby Township,
Lincoln County, Ontario, Canada, assignor to
Bancroft Holdings Limited, Hamilton, Went-
worth, Ontario, Canada, a corporation of On-
tario, Canada

Application November 24, 1936, Serial No. 112,514

5 Claims. (Cl. 198—165)

My invention relates to improvements in tubular belt conveyers of the type shown in my United States Patent No. 2,013,242, September 3rd, 1935, and the object of my invention is to provide an opening device therefor which will move towards and contact the outside face of the conveying tube to split it open for the discharge of contained material.

A further and particular object of my invention is to provide a conveying tube opening device which will not come in contact with the material being discharged, and another object of my invention is to furnish a device of such a character that it can be installed and operated in any desired part of the conveying mechanism.

Another object of my invention is to utilize my apparatus as a means for opening a tube for the reception of material, if so desired.

My invention consists of an opening device for tubular belt conveyers constructed and arranged as hereinabove more particularly described and illustrated in the accompanying drawings in which:—

Figure 1 is a side elevational view of a horizontal length of flexible conveying tube formed by a pair of belts supported by a plurality of pulleys and having my tube opening device positioned thereabove, the tube being in the closed position.

Figure 2 is a similar view to Figure 1, showing the tube opening device in operation, the tube being split open.

Figure 3 is an inverted plan view of the opened tube as shown in Figure 2.

Figure 4 is an enlarged cross sectional view through the belts, being taken through the line 4—4, Figure 1.

Figure 5 is a similar view to Figure 4, being taken through the line 5—5, Figure 2 and showing the discharge of contained material.

Figure 6 is a similar view to Figure 4, showing a unitary tubular conveying belt instead of the pair of belts shown in Figure 4.

Figure 7 is a similar view to Figure 5 wherein the unitary tubular belt is shown split for the discharge of contained material, and

Figure 8 is a cross sectional view through a pair of belts split open at the top for the reception of material.

Like characters of reference indicate corresponding parts in the different views in the drawings.

The type of conveyer to which my device is particularly applicable consists of either a pair of preformed rubber-like trough shaped belts 1 and

2 running face to face to constitute a moving tube, or a unitary tubular belt 3 having a longitudinal slit 4 therein.

As described in my United States Patent No. 2,013,242, the belts 1 and 2 receive material in their troughs 5 and are directed together to form a moving tube wherein the contained material is conveyed. The material is either discharged by separating the belts at the discharge end of the conveyer, or the material is discharged intermediate of the length of the conveyer by means of a suitable discharge mechanism as I shall now describe.

My mechanism is designed to discharge material at the will of the operator and broadly consists of a freely rotatable roller 6 which is positioned above the pair of belts and designed to be moved downwardly so that its pressure against the belts splits them open at the bottom whereby contained material in the belts is discharged. When the roller 6 is moved upwardly or away from the belts so that its pressure against the belts is relieved, the bottoms of the belts come together under the belt tensions whereby the closed tube is again formed and the contained material carried along to the next discharging point. The contacting faces 7 and 8 of the belts are formed with interlocking tongues and grooves 9 and 10. The lower tongue 9 leaves its groove 10 in the split apart portion of the travelling belts and re-enters the groove as the belts come together.

It is to be understood that the pressure exerted by the roller 6 against the belts only splits them apart for a comparatively short distance upon either side of the roller and to insure that the belts remain together for the other portions of their travel a pair of grooved pulleys 11 are positioned underneath and support the belt on either side of the roller 6. The grooves 12 in the pulleys 11 have substantially the same shape and dimensions as the lower half of the tube formed by the belts so that the only portion of the tube that can split open under pressure of the roller is that portion running between the pulleys 11.

The roller 6 is supported and actuated by any suitable mechanism and in the drawings I show it freely contained in the bifurcated lower end 13 of a pivotally mounted arm 14. The upper end of the arm 14 is pivotally connected to the end 50 of a rod 15 which is, in turn, pivotally connected to the upper end of a swingably mounted hand lever 16. When the lever 16 is swung in a clockwise direction the roller 6 is swung downwardly to exert a pressure against the belts and split them

open, and when the hand lever 16 is swung in an anti-clockwise direction the roller 6 is moved upwardly whereby its pressure on the belts is relieved and the belts permitted to close together 5 again under their own tension. In the drawings I also show a hopper 17 for the reception of discharged material.

In Figures 6 and 7, I show the belt 3 of unitary tubular form and this type of belt is mounted in 10 exactly the same manner as the tube formed by the pair of belts 1 and 2 and is also capable of being split apart as illustrated in Figure 6 by a moveable roller 27 having the same operable function as the roller 6. The faces 18 and 19 of the 15 split 4 in the belt 3 are also preferably formed with interlocking tongues and grooves 20 and 21.

In Figure 8, I show a roller 22 positioned underneath my pair of belts 1 and 2 to exert an upward 20 pressure against the belts and split them apart at the top for the reception of material being fed into the belts as from the hopper 23. In this case I show the roller 22 formed with spaced apart 25 rings 24 which constitute a groove for the reception of the lower ribs 25 of the belts. The containing of the ribs within the groove prevents any possibility of the belts accidentally splitting at the bottom as well as the top. Although the belts 1 and 2 or the belt 3 can be of any desired 30 shape, I have shown them of the same form as shown and described in my United States Patent No. 2,013,242. In order to obviate any possibility of the belts riding out of the grooves 12 in the pulleys 11 when the pressure of the roller 6 is 35 applied, I have found it in certain cases desirable to furnish upper riding pulleys 26 which bear upon the tops of the belts in the vicinity of the pulleys 11. The trough belts 1 and 2 are furnished with non-stretchable flexible cores 28, and the tubular 40 belt 3 with a pair of non-stretchable flexible cores 29, both positioned as shown in the drawings.

What I claim as my invention is:

1. In a conveying mechanism, a pliable moving material carrying tube having a longitudinally extending slit-like opening through the wall thereof, a plurality of pulleys upon which the tube is suspended and between which it extends, and

adjustable means moveable towards the side of the tube opposite said slit to exert a pressure against the tube between pulleys to open it along its slotted side opposite the adjustable means for the reception or discharge of material. 5

2. In a conveying mechanism, a pliable moving material carrying tube having a longitudinally extending slit-like opening through the wall thereof, a plurality of pulleys upon which the tube is suspended and between which it extends, and a tube engaging roller moveable towards the side of the tube opposite said slit to exert a pressure against the tube between pulleys to open it along its slotted side opposite the roller for the reception or discharge of material. 10 15

3. In a conveying mechanism, a pair of rubber-like belts adapted to normally travel in face to face contact with each other and having material-carrying cavities in their contacting faces, a plurality of pulleys between which the 20 belts extend, and adjustable means moveable towards the belts between pulleys to exert a pressure against one side of the pair of belts to spread the other sides of the belts apart for the reception or discharge of material. 25

4. In a conveying mechanism, a pair of rubber-like belts adapted to normally travel in face to face contact with each other and having material-carrying cavities in their contacting faces, a plurality of pulleys between which the 30 belts extend, and a tube engaging roller moveable towards the belts between pulleys to exert a pressure against one side of the pair of belts to spread the other sides of the belts apart for the reception or discharge of material. 35

5. In a conveying mechanism, a pliable moving material-carrying tube having a longitudinally extending slit-like opening through the wall thereof, a plurality of pulleys supporting the tube and engaging its slotted portion, and a tube 40 engaging roller moveable towards the side of the tube opposite to the slotted portion to exert a pressure against the tube between pulleys to open it along its slotted side opposite the roller for the reception or discharge of material.

HENRY STINSON JOHNS.
